UNITED STATES PATENT OFFICE.

ADOLPH C. RECKER, OF OAKVILLE, CONNECTICUT, ASSIGNOR TO THE CHASE COMPANIES INC., OF WATERBURY, CONNECTICUT, A CORPORATION.

DESIGN FOR A HANDLE-CAP FOR WHISK-BROOMS AND KINDRED ARTICLES.

59,925.

Specification for Design.

Patented Dec. 6, 1921.

Application filed November 26, 1920. Serial No. 426,660. Term of patent 14 years.

To all whom it may concern:

Be it known that I, ADOLPH C. RECKER, a citizen of the United States, residing at Oakville, in the county of Litchfield and State of Connecticut, have invented a new, original, and ornamental Design for a Handle-Cap for Whisk-Brooms and Kindred Articles, of which the following is a specification, reference being had to the accompanying drawing, forming part thereof.

Figure 1 is a side view of a handle cap for whisk brooms and kindred articles, showing my new design.

Fig. 2 is a top view of the same.

I claim:

The ornamental design for a handle cap for whisk brooms and kindred articles, as shown.

ADOLPH C. RECKER.
